FIG. 3

FIG. 4

FIGURE 1 is a right side elevational view of a lift truck, showing our new design;

FIGURE 2 is a left side elevational view thereof;

FIGURE 3 is a front elevational view of the lift truck; and

FIGURE 4 is a perspective view taken from the rear and above the lift truck.

The dominant features of our design reside in the portions illustrated in solid lines.

We claim:

The ornamental design for a lift truck as shown and described.
